UNITED STATES PATENT OFFICE.

HARVEY BIRCHARD TAYLOR, OF PHILADELPHIA, PENNSYLVANIA.

ANNULAR-JET TURBINE.

Original application filed June 16, 1921, Serial No. 447,891. Divided and this application filed February 11, 1925. Serial No. 8,368.

This invention relates to hydraulic turbines and particularly to turbines of the impulse type. The object of the invention is to provide such a turbine in which the jet will be of generally annular form so as to continuously act on all the runner buckets and to provide buckets for receiving the jet and efficiently guiding the stream lines so as to reduce frictional resistance.

10 Further objects of the invention particularly in the simple symmetrical formation of the buckets will appear from the following description taken in connection with the accompanying drawings, in which—

15 Fig. 1 is a vertical sectional view of a turbine illustrating the invention.

Fig. 2 is a sectional detail view on line 2—2 of Figs. 1 and 3.

20 Fig. 3 is a sectional detail view on line 3—3 of Fig. 1.

Fig. 4 is a section similar to Fig. 2 but illustrating a modification.

Fig. 5 is a view similar to Fig. 1, but illustrating a modified form of turbine, and

25 Fig. 6 is a fragmentary sectional horizontal view showing the guide vanes taken on the line 6—6 of Fig. 5.

In the embodiment of the invention shown in Figs. 1 to 3 the jet J passes downward 30 out of annular orifice 12, the amount of the flow being controlled by varying the thickness of the jet by adjusting the position of the annular wedge 13 in orifice 12. The runner R comprises buckets 14 mounted on a

35 central hub 15 on shaft 16. The hub 15 is cylindrical and the surfaces of the buckets curve into and merge with the cylindrical outer surface of this hub which is continuous between the buckets. The buckets 14 are cup

40 shaped curving backward from the entrance edge 17, as shown in Fig. 2, which is a cross section as cut by a central cylindrical surface, and also curving backward from the vertical center on each side as indicated in

45 Fig. 3 which shows a cross-section cut by a plane surface perpendicular to the axis of the turbine. A continuous shroud ring or band could be used to connect the buckets, but this would only be employed for mechanical reasons and to reduce windage, and

50 would not have any hydraulic function, as it would not be in contact with the water. It will, in many cases, be preferable to omit a continuous band and to form each bucket 14 separately as shown, and when desired the

buckets can be cast separately and bolted or otherwise attached to the hub. By the use of such cup shaped buckets, the water stream entering each bucket can be kept together so as to occupy a minimum volume, 60 and have both its bucket surface and air surface reduced in order to keep the surface friction to the least possible value. The curved form of the bucket in a section normal to the flow, such as Fig. 3, prevents undue spreading of the water stream. If the stream is permitted to spread out it becomes an excessively thin sheet with consequent tendency toward roughening of the surfaces and spraying. The curvature of the buckets 65 transverse to the flow prevents this and tends to keep the water in a compact mass. At the same time, the bucket 14 has small dimensions and therefore does not create excessive windage. The discharge edges of the 70 buckets are so proportioned that the discharged jet will just escape contact with the back 21 of the next succeeding bucket. The inflow edge 17 of the bucket as shown in Fig. 2 will be given an angle suitable to the relative direction of entrance of the jet with respect to the wheel.

The bucket shown in Figs. 1 to 3 is suitable for a moderate specific speed, the speed, however, being much higher than that of 85 impulse turbines of the usual tangential type. If still higher specific speeds are desired, the inflow edge of the bucket would be inclined forward in the direction of rotation to suit a relative direction of entrance 90 having a backward direction with respect to the wheel. This would be suitable for a high peripheral velocity of the runner and as shown in Fig. 4 the buckets 14' have their entrance edges 17' inclined forward, the discharge from the buckets being diagonally 95 backward so as to clear the rear surfaces 21' of the following buckets.

In Fig. 5 the jet J' curves from radial to axial at its base and the thickness of the jet is controlled by the axially movable plunger 25 while an inclined direction or whirl may be imparted to it by the stay and guide vanes 26. The runner R' has its hub conical at its peripheral surface 27 and the buckets 28 are cup shaped somewhat as in Figs. 1 to 3, but having their inner surfaces curving into and merging with this conical surface 27. The buckets 28 have a diagonal inward direction of discharge at the inner edges and 110

a diagonal outward discharge at the outer edges thus differing from the corresponding axial and radial discharge from the buckets 14 of Figs. 1 to 3. In the Fig. 1
5 form the inner surface of the jet J is projected parallel to and in contact with the outer cylindrical surface of the hub 15 but in Fig. 5 the inner surface of the jet J' does not contact with the conical surface 27 of
10 the hub but leaves an intervening air space 30. Although in the embodiments shown the buckets are carried by a conical or cylindrical surface having straight line elements, these elements could be curved so that the
15 buckets would merge with surfaces of revolution generated by a curved line.

As shown, the jet will spread so as to discharge in greatly diverging directions from the bucket, it being possible with this cup-
20 shaped type of bucket to have the discharge extend through an angle approaching almost 180°, and this can be done without requiring a large extent of surface in contact with the jet.

25 I claim:

1. In an impulse turbine the combination with means for forming an annular axially directed jet, of a runner having buckets with jet receiving surfaces curved trans-
30 versely to and in the direction of the stream lines of the jet.

2. In an impulse turbine the combination with means for forming an annular axially directed jet, of a runner having buckets with jet receiving surfaces curved transversely and rearwardly with respect to the stream lines of the jet.

3. In an impulse turbine the combination with means for forming an annular axially directed jet, of a runner having buckets with jet receiving surfaces curved transversely and rearwardly with respect to the stream lines of the jet on each side of said jet.

4. In an impulse turbine the combination with means for forming an annular axially directed jet, of a runner having buckets with jet receiving surfaces curved transversely to the stream lines of the jet, each bucket being concaved and having the entrance portion thereof extending upwardly and being inclined in the direction of runner rotation so that the entrance edge leads the remainder of the bucket.

5. In an impulse turbine the combination with means for forming an annular axially directed jet, of a runner having buckets with jet receiving surfaces curved transversely with respect to the direction in which the stream lines enter the runner; and each of said surfaces at its entrance edge being inclined in the direction of motion of the runner so that the entrance edge leads the remainder of the surface.

6. In an impulse turbine the combination with means for forming an annular axially

directed jet, of a runner having buckets with jet receiving surfaces curved transversely with respect to the direction in which the stream lines enter the runner; and each of said surfaces at its entrance edge being inclined so that the entrance edge leads the remainder of the surface, said inclination being disposed relatively to a plane containing the axis of the runner in a direction conforming to a backward relative whirl of
70 the entering water.

7. In an impulse turbine the combination of a runner with means for forming an axially directed jet extending around substantially the entire circumference of said runner, said runner containing buckets the jet receiving surfaces of which are curved in sections cut by planes containing the runner axis.

8. An impulse turbine having a runner provided with a circular series of buckets and means forming an inlet passage having an annular orifice for directing an axially progressing continuous circular jet against all of said buckets simultaneously, the runner buckets having jet receiving surfaces curved transversely to the stream lines of the jet.

9. An impulse turbine having a runner provided with a circular series of buckets and means forming an inlet passage having an annular orifice for directing an axially progressing continuous circular jet against all of said buckets simultaneously, the runner buckets having jet receiving surfaces curved transversely to the stream lines of the jet on each side of the jet.

10. An impulse turbine provided with a runner and an inlet casing having a jet forming orifice around the runner shaft adapted to form an axially progressing annular jet and to direct the jet against the runner and means co-operating with said orifice for controlling the flow of liquid therethrough, the runner buckets having jet receiving surfaces curved transversely to the stream lines of the jet.

11. In an impulse turbine the combination with a runner, of an inlet casing having a jet forming orifice around the runner shaft adapted to form an axially progressing annular jet and to direct the jet against said runner, and an annular plunger controlling the flow through said orifice, the runner buckets having jet receiving surfaces curved transversely to the stream lines of the jet.

12. An impulse turbine having means for forming an axially progressing circular jet containing tangential components of motion and a runner having a circular series of buckets continuously acted upon by said jet, the runner buckets having jet receiving surfaces curved transversely to the stream lines of the jet.

13. In an impulse turbine the combination

- with means for forming an axially progressing circular jet containing tangential components of motion of a runner having a circular series of buckets continuously acted upon by said jet and means for varying the thickness of said jet to control the speed of said runner, the runner buckets having jet receiving surfaces curved transversely to the stream lines of the jet.
14. An impulse turbine having a runner provided with a circular series of buckets, and means forming an inlet passage having an annular orifice for directing an axially progressing continuous circular jet against all of said buckets simultaneously, the runner buckets having jet receiving surfaces curved transversely and rearwardly with respect to the stream lines of the jet.
15. An impulse turbine having a runner provided with a circular series of buckets, and means forming an inlet passage having an annular orifice for directing an axially progressing continuous circular jet against all of said buckets simultaneously, the runner buckets having jet receiving surfaces curved transversely to the stream lines of the jet and inclined in the direction of rotation so that the entrance edges lead the remainder of their respective surfaces.
16. In a hydraulic impulse turbine of large capacity and high specific speed the combination with a vertical shaft wheel having buckets thereon curved transversely to the stream lines of a jet, of means for forming a jet and directing it against said buckets from above, and varying the size of said jet while preserving its form.
17. In a hydraulic impulse turbine of large capacity and high specific speed the combination with a vertical shaft wheel having buckets thereon curved transversely to the stream lines of a jet containing tangential components of motion of a runner having a circular series of buckets continuously acted upon by said jet and means for varying the thickness of said jet to control the speed of said runner, the runner buckets having jet receiving surfaces curved transversely to the stream lines of the jet.
18. In an impulse turbine the combination with means for forming an annular axially directed jet, of a runner having buckets with jet receiving surfaces curved transversely to the stream lines of the jet, the said jet receiving surface of each bucket having its entrance portion making an angle not greater than 90° with the direction of runner motion and being concavely curved to make a still smaller angle with the direction of runner motion at discharge.
19. In an impulse turbine of large capacity and high specific speed the combination with an axial flow runner having buckets adapted to receive a free jet on one side and pass it through and discharge it on the other side, said buckets curving transversely and increasing in transverse width from the inlet side to the outlet side, of jet forming means adapted to direct a free jet against said buckets on the entrance side, and means for varying the cross sectional area of said jet.
20. In an impulse turbine the combination with a runner, of an entrance casing having an annular jet forming orifice adapted to direct a circular axially progressing jet against said runner, and guide vanes in said casing adjacent said orifice and adapted to impart to said jet tangential components of flow around the axis of the runner, the runner buckets having jet receiving surfaces curved transversely to the stream lines of the jet.
